United States Patent Office

Des. 184,672
Patented Mar. 24, 1959

184,672

DISPLAY STAND

Harold J. Fitzgerald, Whitefish Bay, Wis.

Application June 6, 1958, Serial No. 51,231

Term of patent 14 years

(Cl. D80—9)

Fig. 1 is a perspective view of a display stand showing my new design;

Fig. 2 is a front elevational view on a reduced scale of the display stand; and

Fig. 3 is a side view thereof in elevation as shown in Fig. 2.

I claim:

The ornamental design for a display stand, as shown.
